UNITED STATES PATENT OFFICE.

JEAN MARIE BOCUZE, OF LYON, FRANCE.

ELECTRIC FURNACE.

1,053,563.

Specification of Letters Patent. Patented Feb. 18, 1913.

Application filed October 8, 1912. Serial No. 724,624.

To all whom it may concern:

Be it known that I, JEAN MARIE BOCUZE, a citizen of France, residing at 7 Avenue du Parc, Lyon, Rhône, in the Republic of France, have invented new and useful Improvements in Electric Furnaces, of which the following is a specification.

This invention relates to an improved electric furnace, more especially intended for melting metals, and especially precious metals and alloys, in which the crucible is heated by the radiation from two or more pairs of electrodes heated by the current and between which an arc is formed.

Furnaces of this kind have already been proposed in which the crucible or the electrodes, receives a vertical reciprocating movement, but in these known furnaces the part having the reciprocating movement has at the same time a movement of rotation on itself. These movements present great practical difficulties, especially if applied to the electrodes and if the crucible is to be operated great difficulties are also found in communicating to it simultaneously the movement of rotation and the reciprocating movement, especially by reason of the fact that the crucible, filled with metal in fusion, is very heavy and shocks and sudden movements must be avoided to prevent undue wear and tear and accidents. These difficulties are overcome by the present invention, by the fact that the crucible is given a simple movement of rotation on its axis, while the electrodes are given only a vertical reciprocating movement.

The invention further comprises certain features in the furnace which will be herein-after described and claimed.

The annexed drawing illustrates an example of construction of the improved furnace, in which—

Figure 1 is a vertical section of the furnace; Fig. 2 is a vertical section transversely to that shown in Fig. 1. Fig. 3 is a horizontal section. Fig. 4 is a detail showing the cover of the crucible lowered thereon.

The furnace proper A has, in the construction shown, an octagonal shape. It is formed by a metal jacket provided with a lining of refractory substance. In the interior of this furnace is the plumbago crucible B, which is provided below with a square part B' by which it rests in a sleeve E. This sleeve is provided with a square hole which fits on the end D' of a vertical

shaft D which is supported in a socket T and carries a bevel pinion C rotated by a similar pinion 2 mounted on a driving shaft 3 whereby the crucible can be rotated on its axis in a continuous manner.

The furnace A rests on a metal frame 4 and it is provided with lateral metal plates 5 (Fig. 2) on which are fixed two horizontal pivots Z (Fig. 4). These pivots rest in bearings R which are carried by chairs Q by means of screw threaded rods S which can be rotated by means of spiders U and by means of which the vertical position of the furnace can be regulated. The pivots Z allow of the furnace being swung for casting, for which purpose their ends are squared as at Z' on which a key 8 as shown in Fig. 3, can be engaged. The furnace draws the crucible in this movement by means of a chair W fixed to the frame 4 and in which the crucible carrying shaft D is guided and supported, and by means of a cover P which may be lowered by means of a threaded rod O and hand wheel O' so that it caps the top of the crucible. The vertical rim of this cover is provided with an opening at the place of the casting nozzle of the crucible and the furnace A is provided with a casting channel X at the corresponding position. The screw O is carried by a cap N which is mounted on the cover M of the furnace. This cover can rotate on an axle Y and be fixed in the closed position by a pin M'.

In the construction illustrated the crucible B is heated by two pairs of electrodes G, G' placed at diametrically opposite points (Fig. 3) and passing through vertical openings B' in the furnace. The two electrodes G, G' of each pair are placed one above the other and their points adjacent the crucible are brought toward each other, and carried by sockets V which are themselves fixed in a regulatable manner on a vertical rod H.

The two rods H are joined together at their upper end and can effect a vertical to-and-fro movement with the electrodes, being guided in a support I which comprises four cylinders or sockets. The rods H receive their movement by means of a roller H' operated by an eccentric F keyed on the shaft 3 of the pinion 2. The support I can be moved horizontally toward or away from the furnace as desired, to regulate the position of the electrodes. For this purpose it is provided with a nut J working on a screw

L which can be turned by means of a hand wheel L¹. It is also guided into a slide K bolted to the chair W and supported at its end by a socket of the pillar 7 which at the same time maintains the furnace vertical. The current is conducted to the electrodes in any appropriate way.

During the operation the electrodes and the arcs formed between the furnish the heat necessary for the fusion or combustion of the matters contained in the crucible. The refractory envelop jacket surrounding the crucible prevents any external radiation which is thus concentrated in the crucible. The electrodes having no contact with the fused substances cannot introduce impurities therein, which is especially advantageous for the fusion of precious metals and the manufacture of alloys. Owing to the rotation of the crucible, which may be continuous in the same direction or alternate in both directions, combined with the vertical reciprocating movement of the electrodes, the bath is uniformly heated in all parts. When casting it is sufficient to lower the cover P and to swing the furnace without taking out the crucible, so that the operation is easy.

The invention is not limited to the actual details of the construction represented. There can for instance be any suitable number of electrodes distributed in different fashions around the crucible.

Having now described my invention, what I claim as new and desire to secure by Letters Patent is:

1. In an electric furnace, in combination: a crucible, means for rotating the crucible on its axis, electrodes arranged around the crucible, means for forming electric arcs between the electrodes, and means for imparting to the electrodes a reciprocating movement along the crucible, substantially as described and for the purpose set forth.

2. In an electric furnace, in combination: a crucible, a furnace casing containing and supporting said crucible, means for tilting the crucible and the furnace casing around horizontal pivots, a rotating vertical shaft connected to the crucible so as to carry the same in its rotation, a bevel gear on said shaft, a horizontal shaft, a bevel gear on said horizontal shaft in mesh with the first bevel gear, means for rotating the horizontal shaft, electrodes extending between the crucible and the furnace casing, means for forming electric arcs between the electrodes, a support carrying the electrodes, a

member secured to the furnace and guiding said support vertically, a roller carried by said support, and an eccentric carried by the horizontal shaft and engaging with said roller, substantially as described and for the purpose set forth.

3. In an electric furnace, in combination: 55 a crucible, a furnace casing containing and supporting said crucible, means for tilting the crucible and the furnace casing around horizontal pivots, a rotating vertical shaft connected to the crucible so as to carry the 70 same in its rotation, a bevel gear on said shaft, a horizontal shaft, a bevel gear on said horizontal shaft in mesh with the first bevel gear, means for rotating the horizontal shaft; electrodes extending between 75 the crucible and the furnace casing, means for forming electric arcs between the electrodes, vertical rods carrying the electrodes, a supporting member in which the vertical rods are guided, a slide in which the supporting member is horizontally guided toward and away from the crucible, said slide being fixed to the furnace casing, means for displacing the supporting member in the slide, a roller carried by the vertical rods and an eccentric carried by the horizontal shaft and engaging with said roller, substantially as described and for the purpose set forth.

4. In an electric furnace, in combination: 90 a crucible, a furnace casing containing and supporting said crucible, a cover for said crucible, means for lowering said cover upon the crucible and clamping the latter in the furnace casing when desired, a laterally pivoting cover for the furnace, upon which the crucible cover is supported, means for tilting the crucible and the furnace casing around horizontal pivots, means for rotating the crucible on its axis, electrodes extending 95 between the crucible and the furnace casing, means for forming electric arcs between the electrodes, means supported by the furnace casing and carrying the electrodes so that the latter are movable and adjustable 100 thereon and means for imparting to the electrodes a reciprocating movement along the crucible, substantially as described and for the purpose set forth.

In testimony whereof I have signed my 110 name to this specification in the presence of two subscribing witnesses.

JEAN MARIE BOCUZE.
